MEANS FOR IDENTIFYING AND REPRODUC-
ING COLOR HARMONY

Thomas F. Lodwick, Mystic, Iowa

Application January 18, 1939, Serial No. 251,589

5 Claims. (Cl. 41—6)

The principal object of this invention is to provide a method of and means for identifying and reproducing color harmony which enables the user to reproduce accurately and quickly, the color desired.

A further object of my invention is to provide a method of and means for identifying and reproducing color harmony which provides an accurate and precise method of matching hues, 10 chroma, and value of a color.

A still further object of this invention is to provide a means for quickly identifying, comparing and selecting colors from a graduated cross indexed color identification color system, which not 15 only shows the colors and accurately names them, but which gives the mixing formulas and all of the complementary colors to that particular color selected.

A still further object of this invention is to provide a method of and means for identifying, and reproducing color harmony that is economical to manufacture and which provides an efficient, precise method of accomplishing its result.

These and other objects will be apparent to 25 those skilled in the art.

My invention consists in the construction, arrangement and combination of the various parts of the device and methods employed in its use, whereby the objects contemplated are attained 30 as hereinafter more fully set forth, pointed out in my claims and illustrated in the accompanying drawings, in which:

Fig. 1 is a top elevational view showing the arrangement of the hue matching directory.

Fig. 2 is an end elevational view of the hue matching directory more fully illustrating its structure.

Fig. 3 is an enlarged side sectional view of one of the binding elements used in the construction 40 of the hue matching directory.

Fig. 4 is a view of one of the pages of my directory showing one of the mixing tables or charts.

Fig. 5 is a rear view of one of the color tone 45 cards incorporated in my directory.

Heretofore, color harmony has been largely left to guess work and to the ability of the painter. This manner of obtaining a harmony in color tones is very unsatisfactory. These painters and 50 color workers have no concrete basis upon which to establish a certain color tone or know that the paint, when dry, will achieve the results desired in a given instance. Heretofore, there has been no way of accurately foreseeing changes 55 occurring in the color tone of a given paint from

its moist state to the drying stage and as its color tone has an entirely different characteristic from dry over the wet state. There is no way of definitely knowing the exact color produced except by the trial and error method. I have 5 overcome such disadvantages as will be appreciated and as will hereinafter be more fully set forth. My process or method involves the use of a cross indexed complete color tone directory and method for making or producing the tones 10 of the desired and specific characteristics.

Referring to the drawings, I have used the numeral 10 to designate a rigid base board upon which are mounted the directories 11 and 12. These directories are made up of a plurality of 15 leaves of color tones progressively graded as to change of values of the respective colors of the visible spectrum. I have used the numerals 13 and 14 to indicate hollow post members rigidly secured to the base 10 and slidably embracing a 20 locking bar or rod 15 as shown in Fig. 5 of the drawings. It is upon these locking members and tube members that I place the various leaves of my directories which I will now describe. The numeral 16 indicates a plurality of color tone 25 cards operatively mounted on the binding elements comprising the members 13, 14, and 15. On each specific page of this directory is a plurality of these color tone cards progressively valued from the deeper values of a specific tone 30 to the lighter values as illustrated in Fig. 1 of the drawings. Similarly, the numeral 17 indicates color tone cards operatively mounted or bound together to form the directory 12. These color 35 tone cards mounted in the directory 12 are complementary colors of those mounted and listed in the directory 11. Each of these color tone cards is bound to the base by three of the binding elements in this specific instance so that any color tone card within the directory may be removed at will without disturbing the other cards 40 of the series. Separating each of these color value graduation indexes is an identification page or sheet 18 and 19 for identifying the colors directly adjacent this page within the directory 45 11 and the directory 12 respectively. Upon these pages 18 and 19 is printed indicia describing the specific tone, naming it, and giving all references relative to obtaining the desired value and giving a color harmony reference for arriving at 50 the complementary color of the base color selected, and also the colors necessary for obtaining a balanced three or four tone harmony. The numeral 20 indicates reference tabs spaced throughout the directory for quickly and easily 55

finding the color or tone specified on the identification sheets 18 and 19. I have used the numeral 21 to designate one of the pages of the directory containing one of the mixing tables for obtaining a given color as selected from the directory. This page has thereon indicia for supplying a formula for obtaining the desired color thereon and is referred to upon the directory pages 18 and 19 adjacent the color tone cards 16 and 17.

My method employs the use of the directory as shown in the drawings and I will now describe the various stages outlining my method of and means for identifying and reproducing color harmony. When a certain color tone has been decided upon for use in a specific instance, this tone is identical within either of the directory portions 11 or 12. Reference is then made to the reference made directly adjoining or adjacent to the color tone selected and all of the characteristics, formulas, and other identification is readily ascertainable. Referring to Fig. 1 of the drawings, it will be noted that upon the directory 11, I have shown a specific color tone, in this case indicated upon the color tone card 16. This tone card by reference to the reference page 18 shows that the color is identified as "magenta rose" and also identifies the hue as to its respective relationship to the other hues within the directory, the chroma, the permanence of the hue, and a reference to the mixing table. This specific mixing table I have shown in Fig. 4 and from this table, there is shown the proportions of mixture to obtain the tone as indicated opposite each of the color cards 16. Furthermore, the indicia upon this reference page indicates the hue that is the complement of the one selected and also shows which hues combine with this specific hue for obtaining either the balanced three tone harmony or a balanced four tone harmony in conjunction with this hue. Thus all of the necessary indicative references are listed upon the pages 18 and 19 with respect to the hues shown on the color tone cards 16 and 17 respectively. Referring to Fig. 5 of the drawings, it will be noted that upon the back of the color tone card 16, and in this specific instance, the one having the lower value has printed upon its rearward side an identification number. The first two numbers, including the zero, identify the hue painted upon the forward side of the color card 16. The third number indicates the chroma of that particular tone and the last number indicates the tone number as applied to the mixing table. Thus, an individual card has thereon the identification necessary to convey the descriptive properties of the particular hue with reference to the directory and its basic characteristics may be found by reference to the numbers upon the back of the color tone card. Any card within either the directory 11 or 12 may be removed by sliding the portion 15 of the binding element until the shorter end is out of engagement with the tubular standard 14, and each card in the directory is supported upon three of these binding elements. Thus a card may be detached from the directory and used as a reference or matching unit. Thus every characteristic of an individual color or tone is ascertainable within my directory.

In arriving at the variance in values between successive color tone cards, I have employed a mathematical sequence of proportion between a basic color and white. Thus in obtaining tone 2 which identifies on the reference page 18 the tone of the lower valued card 16,

the ratio between oil color or like and white is 1 to 1. In graduating to the tone of the next highest value, the proportion of white to the basic color is 3 to 1. For obtaining the next highest value, the proportion of white, or value reducing agent, to the basic color is 7 to 1, and so the colors are progressively valued 15 to 1, 31 to 1, 63 to 1, and 127 to 1, to obtain the values shown on one page containing a series of cards 16. This may be carried out to any degree by taking the proportion of white in the preceding value and doubling this amount and then adding one part. This gives a uniform basis for obtaining accurate value reduction relative to a specific color and also assures the consistency of changing tone values. Thus, with a given brand of paint, a color tone may be produced accurately at any time and everyone using my directory and method will be assured of a color having a tone value that is constant and fixed in every other directory and for every other use. My directory accurately gives the complementary hue which cannot be accomplished by mixing visual comparison, and in the case of balanced three tone and four tone harmony, it is very difficult to ascertain visually the proper hues making up a harmonious combination. With the methods now employed, it is merely a matter of trial and error with no precision and accuracy. In fact, the balanced color harmony is left to the eye of the decorator, painter or the like. With my method, the accurate and precise hues are listed that balance and harmonize with the given or base hue. Heretofore, when a certain color had been selected, it was impossible to accurately and quickly reproduce the tone desired. With my method, the tone selected can be accurately and quickly reproduced with the references given, and without any guess work or experimentation, that tone can be reproduced at any time with precise results and accurate toning quality. This phase has heretofore been one of the most difficult to accomplish where colors and tones are concerned. My method provides for the precise graduations of values uniformly throughout the color spectrum which hitherto has been impossible and by following my formula for the progression of values, absolute uniformity of color variation is attained.

Thus it will be seen that I have provided a method of and means for identifying and reproducing color harmony which fulfills all of my objects and which quickly and accurately gives all information necessary concerning any selected tone or hue from the initial selection through the preparation and reproduction of the color, the complement of the hue and the balanced harmonizing with a plurality of other hues.

Some changes may be made in the construction and arrangement of the various portions of my directory and in the method of and means for identifying and reproducing color harmony without departing from the real spirit and purpose of my invention and it is my intention to cover by my claims any modified forms of structure, the use of mechanical equivalents or variations in the method employed which may be reasonably included within their scope.

I claim:

1. The means for identifying and reproducing color harmony comprising, a plurality of tone value cards adjacent each other, a reference page adjacent said cards including identification of the hue and chroma on said cards, indicative references concerning said cards, and references

- indicating harmonious and complementary colors.
2. In a directory for color identification and reproducing, a base member, a plurality of binding elements secured to said base member, a directory operatively mounted on said binding elements comprising, a plurality of color tone cards operatively secured by said binding elements and of progressive values, a color reference page operatively mounted on said elements and adjacent said color tone cards, indicative reference indicia on said reference page, a plurality of binding elements secured to said base member spaced apart and parallel with said first mentioned binding elements and comprising, a plurality of color tone cards complementary to said color tone cards of said first mentioned directory and operatively mounted on said second mentioned binding elements, a color reference sheet operatively mounted on said second mentioned binding elements adjacent said color tone cards, indicative reference indicia on said reference page, indicia for identifying each of the color hues on said color tone cards, indicia adjacent each of said color tone cards indicating its complementary and harmonizing colors, and accurate information indicia for reproducing each of said tonal values indicated on said color tone cards.
3. In a directory for color identification and reproduction, a plurality of binding elements, a directory operatively mounted on said binding elements comprising, a plurality of color tone cards operatively secured by said binding elements and of progressive values, a color reference page operatively mounted on said elements and adjacent said color tone cards, indicative reference indicia on said reference page, a second set of binding elements, a directory operatively mounted on second set of binding elements comprising, a plurality of color tone cards complementary to said color tone cards of first mentioned directory, a color reference sheet operatively mounted on said second binding element adjacent said color tone cards, indicative refer-

ence indicia on said color reference sheet, indicia for identifying each of the color hues of said color tone cards, indicia adjacent to said color tone cards indicating its complementary and harmonizing colors, and information indicia for reproducing each of said tone values indicated on said color tone cards.

4. In a means for identifying and reproducing color harmony, a plurality of colored cards each progressively reducing in value the color of said card on succeeding adjacent color tone cards, indicia on each of said cards indicating reproduction of said tonal value of each of said color tone cards, indicia adjacent said color tone cards for the identification of hue and chroma of each of said color tones, and indicia for indicating the harmonious and complementary hues to each of said color tone cards.

5. In a means for color identification and reproduction, a base member, a directory operatively mounted on said base member comprising, a plurality of color tone cards operatively secured to said base member and of progressive values, a color reference page operatively mounted on said base member and adjacent said color tone cards, indicative reference indicia on said reference page, a second directory operatively mounted on said base member spaced apart and parallel with said first mentioned directory and comprising, a plurality of color tone cards complementary to said color tone cards of said first mentioned directory and operatively mounted on said base member, a color reference sheet operatively mounted on said base member adjacent said second mentioned color tone card, indicative reference indicia on said second said mentioned base, indicia for identifying each of the color hues and chromas on said color tone cards, indicia adjacent each of said color tone cards indicating its complementary and harmonizing color, and accurate information indicia for reproducing each of said tonal values indicated on said color tone cards.

THOMAS F. LODWICK. 45
